CORNER GUARD FOR CARTONS

Herman E. Stock, New Haven, Conn.

Application January 16, 1939, Serial No. 251,245

1 Claim. (Cl. 229—49)

This invention relates to corner guards for cartons and has for an object to provide a metal reinforcement which may be bound into a corrugated box or carton with prongs, one of the sections of the guard being free to permit it being folded down over another section to permit storage of the carton in flat condition, the free section being unfolded along a weakened line to a position of 90 degrees which will permit the carton being opened and set up and the free section hooked in place to provide a corner reinforcement which will be light, strong and durable, and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming part of this specification:

25 Figure 1 is a perspective view of a carton with a portion of the top broken away to expose a corner guard constructed in accordance with the invention.

30 Figure 2 is a cross sectional view taken on the line 2—2 of Figure 1 drawn to enlarged scale.

35 Figure 3 is a plan view of the blank from which the corner guard is formed.

Figure 4 is a side elevation of the corner guard in set up position.

35 Referring now to the drawing in which like characters of reference designate similar parts in the various views, the corner guard is formed from a single blank of metal in the form of a square divided by diagonal lines into four triangular sections of equal size, one of the sections being removed, as shown in Figure 3, except for two diagonally extending lugs 10 on the adjacent section 11. The blank is scored along the diagonal lines as indicated at 12 and 13 and the lower section 14 opposite the upper section 11 is provided with slots 15 to receive the lugs 10 when the blank is folded into pyramid shape to engage the corner of the carton in use.

The section 16 intermediate the upper section 11 and lower section 14 is provided with struck out prongs 17 and the lower section is provided with struck out prongs 18. The corner guard above described is bound into the carton by the carton manufacturer inserting the prongs 17 and 18 of the sections 16 and 14 into two of the walls of the corner of the carton 19, as best shown in Figure 1. As the carton must be delivered and stored flat the lower section 14 and intermediate section 16 having the prongs must be folded flat along the weakened score line 12. When the carton is set up for use the operator, by the act of opening the carton unfolds the sections 14 and 16 on the weakened score line 12 to a position of 90 degrees relatively to each other. This will permit the top section 11 with the lugs 10, being folded down to engage the bottom section 14 whereupon the lugs 10 may be engaged through the slots 15 to set up the corner guard.

From the above description it is thought that the construction and operation of the invention will be fully understood without further explanation.

What is claimed is:

25 A corner reinforcement for cartons, comprising a single blank of sheet metal of substantially rectangular contour divided by diagonal intersecting score lines into three contiguous triangular sections, there being openings in the free edge portion of one of the end sections, tabs on the free edge portion of the other end section adapted to be hooked into said openings, said sections being bent on the score lines to form a pyramid guard for insertion in the corner of a carton, one of said end sections and the intermediate section being provided with prongs struck out from the body of the sections and adapted to be engaged through two contiguous walls of the carton, said tabs being detachable from said openings to permit the guard being folded along one of said score lines to dispose the intermediate section flat upon the end section carrying the tabs, to permit the carton being stored and transported in collapsed flat form.

HERMAN E. STOCK.
